UTILITY UNIT FOR CAMPERS OR THE LIKE

James C. Corbett, Salt Lake City, Utah, assignor to
Kenneth D. Slabaugh

Filed Oct. 4, 1971, Ser. No. 186,587

Term of patent 14 years

Int. Cl. D23—02; D6—05

U.S. Cl. D23—50

FIG. 1.

FIG. 2.

FIG. 3.

FIG. 4.

FIG. 5.

FIG. 1 is a front elevational view of a utility unit for campers or the like showing my new design;

FIG. 2, a top plan view;

FIG. 3, a rear elevational view;

FIG. 4, an end elevational view, viewed from the left of FIG. 3; and

FIG. 5 is an end elevational view opposite to that shown in FIG. 4.

I claim:

The ornamental design for a utility unit for campers or the like, substantially as shown.
